UNITED STATES PATENT OFFICE.

CARL E. BAUER, OF HAMMOND, INDIANA.

CULTIVATOR.

Application filed November 16, 1922. Serial No. 301,285.

To all whom it may concern:

Be it known that I, CARL E. BAUER, a citizen of the United States, residing at Hammond, in the county of Lake and State of Indiana, have invented a new and useful Improvement in Cultivators, of which the following is a specification.

This invention relates to improvements in cultivators. My improved cultivator is simple in construction and design, thus lowering the cost of production. It is also so designed that it can be easily operated.

A device embodying the features of my invention is shown in the accompanying drawings, in which Figure 1 is a view in side elevation, Fig. 2 is a top plan view, Fig. 3 is a view taken as indicated by the line 3 of Fig. 1, Fig. 4 is a view taken as indicated by the line 4 of Fig. 3, and Figs. 5 and 6 are views of different kinds of cultivator tools that can be used with the device.

As shown in the drawings, 10 indicates a pair of longitudinally arranged parallel frame members made preferably of channel iron, as shown. Each of these members is provided with a slight offset, as shown. The frame members 10 are joined near their forward ends by a pair of cross members 11, on which are mounted the motor 12, here shown as an internal combustion engine of the air cooled type.

Near their forward ends, the frame members 10 are also joined on their under side by a plate 13, carrying pivotally supported at each end on its under side, in the usual manner, steering knuckles 14, which in turn carry the main supporting wheels 15. The frame members 10 carry at their rear ends substantially vertically arranged members 16 joined at their upper ends by the horizontal member 16^a and carrying at their lower ends the rear supporting and driving wheels 17. It will be noted that the frame members 10, thus joined at their forward ends and their rear ends, form a rigid frame. The upper ends of the members 16 are provided with bearing supports 18 in which are rotatably mounted the controlling handles 19. The forward ends of the controlling handles 19 are rotatably supported in the bearing members 20, which are carried by the frame members 10. The forward ends of the controlling handles 19 are provided with depending arms 21, which are joined to the connecting rod 22, which joins the steering

knuckles 14, in the usual manner. The rear ends of the handles 19 are bent downwardly, as indicated by 19^a, so that steering may be effected by twisting the handles 19, thus turning the steering knuckles and wheels 15. It is to be noted also that steering may be effected by merely raising the wheels 15 and swinging the machine about on the wheels 17.

About midway between their ends, the frame members 10 carry a counter-shaft 23 (see Fig. 3). The counter-shaft 23 is provided at each end with a yoke 24, having a downwardly depending sleeve 25 mounted on a shaft 26 carrying on its lower end a cultivating tool 27. Each shaft 26 is provided at its upper end with a bevel gear 28 meshing with a bevel gear 29 on the shaft 23. The shaft 23 is provided near its center with a sprocket wheel 30 adapted to be driven by a chain 31, which in turn is driven by the motor 12. It will be noted that, by this construction, the cultivating tools 27 will be rotated.

Each cultivating tool 27 comprises a circular plate 27^a mounted on the end of the shaft 26. Detachably mounted on the plate 27^a are the cutters 27^b, each adapted for easy removal by removing the cap screws 27^c, which are threaded into the plate 27^a. By means of this construction, it will be noted that the cutting tools 27^b may be easily and quickly removed and other tools of different forms, as suggested in Figs. 5 and 6, as desired, substituted.

The counter shaft 23 is provided at its ends with sprockets 32 and the rear wheels 17 are provided with sprockets 33. The sprockets 32 and 33 are joined by the chains 34. In this manner the rear wheels 17 are given rotation by the motor 12 in a direction tending to drive the cultivator forward. By this construction, the rear wheels 17 operate both as supporting wheels and driving wheels. It will be noted, however, that these wheels may be easily lifted from the ground by merely raising the handles 19^a, thus stopping the driving as desired without stopping the motor or cultivating tools. The location of the motor or prime mover 12 enables ready changing of the center of gravity as the machine tilts with respect to the axle 14 by raising of the handles 19^a. Being relatively small in diameter or size, wheels 17 are of minimum weight so as to facilitate the lifting of the

handles 19^a and the tilting of the machine as referred to.

The yokes 24 with their depending sleeves 25 are rotatably mounted on the counter-shaft 23. These sleeves 25 carry, at their lower ends pivotally mounted thereon at 35', a pair of bars 35 joined at their rear ends by the cross bar 36. The members 16, about midway between their ends, are joined by 10 a horizontal bar 37. The lower edges of the members 35 are provided with a series of notches 38. By this construction, it is possible to vary the angularity between the sleeves 25 and the members 16 by raising the 15 members 35 and engaging different notches with the bar 37. It is possible, therefore, to move the cultivator tools in various positions, such as indicated by the broken lines in Fig. 1. By this means, the cultivator 20 tools may be set so that they will engage the ground deeply or only slightly; or, if desired, they may be swung to the rear and disengaged entirely from the ground. Also, if desired, they may be pushed to a position 25 forward of the vertical. By thus slanting the sleeves 25 forwardly or backwardly and equipping the plates 27^a with the proper shaped tools, the rotation of the tools against the ground being cultivated may be 30 made to serve to assist in propelling the cultivator. For example, tools shaped such as suggested in Figs. 5 and 6, or tools having a substantially cork-screw shape, may be employed; and such tools with the proper 35 angularity given to the sleeves 25 will, when rotated, assist in propelling the cultivator.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to 40 claim all novelty inherent in my invention as broadly as possible in view of the prior art.

What I claim as new and desire to secure by Letters Patent, is:

- 50 1. A cultivator including a frame, a prime mover on said frame adjacent the forward end thereof, a relatively large non-driven ground wheel journaled on the frame and having its axis below said prime mover and adjacent said forward end of the frame, a cultivating means on said frame in the rear of said axis, a ground wheel driven from the prime mover, the latter ground wheel being relatively small with 55 respect to the non-driven ground wheel and supported on said frame in the rear of said cultivating means, and means extending from the frame engageable adjacent the rear of the machine to tilt the latter.
- 60 2. A cultivator including a frame having

an upstanding member adjacent one end thereof disposed partly above and partly below the frame, a relatively small ground wheel carried by and adjacent the lower end of said member, a cultivating means on said frame operable in front of said wheel, a prime mover on the frame adjacent the forward end thereof to operate said wheel and cultivating means, a non-driven ground wheel relatively large with respect to the first mentioned ground wheel; in advance of the cultivating means, the axis of the non-driven ground wheel being below the prime mover and adjacent said forward end of the frame, and a controlling handle extending from the frame to the rear of said member and supported by said member adjacent the upper end of the latter.

3. A cultivator including a frame, a shaft journaled transversely thereof, cultivating means depending from and in driven relation to said shaft, an arm extending rearwardly from said cultivating means, said frame having spaced upstanding members in the rear of said cultivating means disposed partly above and partly below the frame, ground wheels carried by said members adjacent their lower ends, controlling handles extending from said frame and supported by said upstanding members adjacent the upper ends of the latter, a rod spanning said members, and said arm having means for adjustable attachment to said rod.

4. A cultivator including a frame provided with front wheels, cultivating devices disposed one substantially in line with and rearwardly of each front wheel, means on the frame to support and drive said devices, upstanding members at the rear of said frame, rear wheels carried by said members, controlling handles in divergent relation extending from the frame and supported by said members, means connecting said members, arms extending intermediate said members and attachable to the latter means, and said arms having forward outwardly offset connections to said devices.

5. A cultivator including a frame having upstanding members, cultivating means carried by the frame, said cultivating means having arms extending rearwardly therefrom and disposed intermediate and attached to said members, controlling handles, the forward ends of said arms being located outwardly of the adjacent portions of the handles, and said handles being in substantially crossed relation to and above the respective arms and supported by the upstanding members adjacent the outer side surfaces of the latter.

6. A cultivator including a frame having longitudinally disposed substantially parallel frame members, a motor supported thereby adjacent one end, front wheels be-

tween which the motor is located, steering knuckle connections between said frame members and wheels, upstanding members adjacent the rear ends of said longitudinal frame members, rear wheels carried by the upstanding frame members at their lower ends, controlling handles supported by said upstanding members adjacent the outer sides of the latter, said controlling handles adjacent their forward ends having connections with the steering knuckle connections intermediate the longitudinal frame mem-
bers, shaft means journaled on said longitudinal frame members driven from the motor, a cultivating device behind each front 15 wheel driven from said shaft means, arms extending from said devices in substantially crossed relation to the longitudinal frame members, and means to secure said bars to and intermediate the upstanding frame 20 members.

Witness my hand and seal this 14 day of November, 1922.

CARL E. BAUER. [L. s.]
